UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL MACHINE.

Application filed June 16, 1922. Serial No. 568,711.

To all whom it may concern:

Be it known that I, DAVID S. KENNEDY, a citizen of the United States, residing at Brooklyn, in the county of Kings and State 5 of New York, have invented certain new and useful Improvements in Typographical Machines, of which the following is a specification, reference being had therein to the accompanying drawing.

10 My invention relates to typographical machines, such as linotype machines of the general organization represented in Letters Patent of the United States No. 436,532, to O. Mergenthaler, wherein circulating matrices are released from a magazine in the order in which their characters are to appear in print and then assembled in line, the composed line transferred to the face of a mold, the mold filled with molten metal to form a 15 slug or linotype against the matrices which produce the type characters thereon, and the matrices thereafter returned through distributing mechanism to the magazine from which they started. More particularly, it 20 relates to those machines equipped with a plurality of fonts of matrices, any one of which may be brought into action at will.

25 The fonts most commonly employed each comprise about ninety different matrices, which vary widely in body size or thickness 30 in the respective fonts, reaching as high as 18 pt. or more. While these regular fonts thus afford a wide choice to the compositor, there are certain classes of work which require even larger sizes of matrices. To meet 35 this requirement, the machines have been equipped with one or more supplemental magazines containing an auxiliary font or fonts of the required size (which may be 40 anywhere from 24 pt. to 36 pt. or more), or containing any other fonts desired to supplement the regular fonts of the main magazines. In one class of such machines (see Kennedy Patent No. 1,136,535), both the 45 main and the supplemental magazines are movably arranged so that different selected ones thereof may be brought into operative relation to a single distributing mechanism at the top and a single assembling mechanism at the bottom. This arrangement permits the free mixture of the matrices of the 50 regular fonts with those of the auxiliary fonts, but it does not allow the matrices of either the regular fonts or the auxiliary 55 fonts to be used or mixed with each other.

In another class of such machines (see Rogers Patent No. 1,270,328), the magazines of the two series are stationary and the distributing and assembling mechanisms are so constructed that the matrices of the main 60 and auxiliary fonts, either alone or conjointly, may be mixed together in the same line. In machines of this latter class, however, certain disadvantages arise which are not present in machines of the former class. 65

My present invention contemplates a machine possessing the principal advantages without the attendant disadvantages of both classes of machine above referred to. To this end, the machine is equipped with a plurality of distributors cooperating continuously with all the magazines of the two series and with a single assembling mechanism common to all the magazines of both series, and the magazines are mounted in 70 such manner that any selected magazine of either series may be moved into operative relation to the common assembling mechanism without disturbing the cooperative relation 75 existing between the magazines and the distributors. The exact arrangement and relationship of the parts will be fully pointed out in the detailed description to follow.

In the accompanying drawings, I have shown my invention only in preferred form 85 and by way of example, and it will be understood that many changes and variations therein and in its mode of application may be made and still be comprised within its spirit. Generally speaking, I desire it to 90 be understood that I do not limit myself to any specific form or adaptation, except in so far as such limitations are specified in the claims.

Referring to the drawings:

Figs. 1, 2 and 3 are side, front and rear elevations of my improved machine; and

Fig. 4 is a view of a detail.

The matrices X of the regular fonts are stored in the series of superposed main 100 magazines A, while those of the auxiliary fonts are stored in the series of superposed supplemental magazines B; it being noted that these two series of magazines are arranged side by side or in tandem. In the 105 embodiment illustrated, only two magazines are shown in each series, but it will be understood that a greater number may be employed if desired. The main magazines A are of the customary trapezoidal form, hav- 110

ing their grooved channels (90 in number) converging toward their lower ends and spaced apart to accommodate the smaller matrices of the regular fonts, whereas the 5 supplemental magazines B are of plain rectangular shape, having their grooved channels (34 in number) parallel throughout and more widely spaced apart in order to accommodate the larger matrices of the auxiliary fonts. Both the main and supplemental magazines are each provided with escapements C, as usual.

The matrices are distributed into the various magazines by two character distributors E, each serving the opposite magazines of the two series, and which are constantly connected to the magazines through the medium of magazine entrances D and D¹, the former leading to the main magazines A and the latter to the supplemental magazines B, all substantially as shown and described in the Rogers Patent No. 1,270,328 before referred to or as embodied in the commercial Model 24 machine.

25 The assembling mechanism, unlike the distributing mechanism, is capable of cooperating with one magazine only of each series. Thus, there is employed a common assembler entrance having its main portion 30 F arranged to cooperate with a selected one of the magazines A and a supplemental portion F¹ arranged to cooperate with a selected one of the magazines B, it being observed that both portions discharge the 35 matrices they receive onto the assembling belt F² which delivers them to the usual assembler (not shown) wherein they are composed in line. The release of the matrices from the two selected magazines is effected 40 by two distinct sets of escapement actuating devices, one set for each series of magazines, and each comprising a bank of pivoted levers C¹ and a corresponding bank of operating reeds C². The reeds of one 45 set are actuated from the main keyboard C³ and those of the other set from the supplemental keyboard C⁴.

50 The use of the foregoing arrangement is permitted and provided for by mounting the magazines of the two series in such manner that any selected magazine of either series may be brought into operative relation to the common assembler entrance and the corresponding set of escapement actuating devices without disturbing the cooperative relation existing between the magazines and the distributing mechanism. To 55 this end, the main magazines A are carried by separate base frames A¹ pivotally connected at their upper ends, as at A², to fixed supporting brackets G (only one of which is shown herein). The supplemental magazines B are likewise carried by separate base frames B¹ pivotally connected 60 at their upper ends, as at B², to the fixed

supporting bracket G at one side and to a further supporting bracket G¹ at the opposite side, it being pointed out that the pivotal axes of the supplemental magazines are coincident with those of the main magazines. According to the foregoing construction, the magazines of each series are free to be rocked upwardly and downwardly about independent axes located below and close up to the distributors so that when any 70 selected magazine of either series is brought into operative position, the extent of rocking of the magazine entrances D or D¹ will be so slight as not to interfere with their operative relation to the distributors, which 75 may thus continue to distribute the matrices into the magazines at all times. As a result, it follows that the matrices from anyone of the magazines or any combination thereof may be mixed together in the same line, notwithstanding the fact that the selection of the desired magazines involves the raising or lowering of the magazines of either 80 or both series. I believe myself to be the first to provide an arrangement of this kind, 85 and I lay claim thereto broadly. The arrangement greatly simplifies the construction of the parts, and moreover enables the matrices, particularly the auxiliary matrices, to be composed in line in a very expeditious and efficient manner.

Attention is directed to the fact that the magazines of each series, instead of being parallel as usual, are arranged in planes converging toward their upper ends, see 100 particularly Fig. 1. This converging or fan-shaped arrangement of the magazines is also believed to be entirely new and is very advantageous for a variety of reasons. For instance, it not only allows the pivotal axes of the magazines to be brought closer together as desired, but in addition, it enables the magazine entrances (the lower or rear ones in particular) to conform more nearly to their regular curvature, and moreover, permits the magazines to approximate a common or uniform angle when in operative position, notwithstanding their separate pivotal mounting.

115 The swinging of the base frames (which in each series constitute a shift frame) to effect the interchange of the magazines may be carried out in any desired manner. In the present embodiment, the shifting means employed in connection with the main magazines A is or may be precisely the same as that illustrated and described in my prior Letters Patent, No. 1,386,786, to which reference may be had for full details. For the purpose of this case, it need only be pointed out that the selection of the desired magazine A is controlled by the hand lever H which when depressed at its forward end brings the lower magazine into operative position and which when raised brings the upper 120 125 130

magazine into operative position. Substantially the same form of mechanism is employed for the supplemental magazines B. Thus, there is provided a single pair of 5 toggle links K¹ and K² jointed together at K³ and adapted to be extended and collapsed by a second hand lever K.

As shown in Fig. 2, the two hand levers H and K are arranged side by side in close 10 proximity to each other and are pivoted to a fixed supporting bracket G², as at K⁴, so as to turn about a common axis. The hand lever H is provided with a small pivoted lever H¹ having at its forward end a double 15 grip portion H² and connected at its rear end to a locking pin H³ which passes through a hole in the lever H and engages in a similar hole formed in the hand lever K. When thus coupled together, the two hand levers 20 may be operated as one, causing the magazines of the two series to be raised or lowered simultaneously to bring two different magazines (one in each series) simultaneously into operative position. This simultaneous 25 shifting of the magazines is useful in certain cases when it is desired or necessary to mix matrices from two particular fonts or sets. On the other hand, other conditions may require that the matrices from any one of the 30 main magazines be mixed with matrices from any one of the supplemental magazines. This will involve the independent shifting of the two series of magazines, which is permitted by operating the pivoted 35 lever H¹ to withdraw the locking pin H² so as thus to disconnect the two hand levers. In other words, the arrangement is such that the magazines of the two series may be shifted, either independently or simultaneously, 40 to bring different selected magazines into operative position.

Mechanism like that disclosed in my prior Patent No. 1,386,786, above mentioned, is employed to facilitate the removal of the 45 magazines in each series. Such mechanism is herein shown only in connection with the supplemental magazines and comprises the pair of rotary cams J fixed to the opposite ends of the transverse rock shaft J¹ journaled in suitable bearings of the lower base frame B¹. These cams are arranged to cooperate with rollers G³ carried by suitable brackets on the fixed machine frame and are rotated by the operating handle J³, 50 which may be made integral with one of the cams as shown or attached separately to the rock shaft. Normally, and when at rest, the cams J stand clear of the rollers G³ so as to permit the free and unimpeded shifting of 55 the magazines, but, upon the operation of the hand lever J³, the cams are brought into engagement with the rollers and then by their continued rotation swing the entire 60 magazine structure upwardly about the pivotal axes of the base frames to an extent

sufficient to locate the lower magazine above the assembler entrance. As the magazines are thus raised, they are also separated vertically from each other, this being done by means of the links J² pivotally connected at their lower ends to the cams J and at their upper ends to the upper base frame B¹, the points of attachment of the links to the cams being such that the upper base frame will be 70 swung upwardly about its pivotal axis to a further extent than that of the lower base frame. Counterbalancing devices (also like those disclosed in my said patent) are employed to assist the operator in performing the above operations, these devices comprising the arm J⁴, the centrally pivoted lever J⁵, and the strong spiral spring J⁷, all arranged and operating as fully set forth in 75 said patent.

It is necessary or at any rate desirable 80 that the raising of the magazine structure in the foregoing manner be effected only when the lower magazine is in operative relation to the assembler entrance. According to the present invention, therefore, locking means 85 are provided to prevent the operation of the hand lever J³ except when the lower magazine is in such position. In the embodiment illustrated, such locking means is in the form 90 of a hooked shaped device J⁸ fixed to the machine frame in position to cooperate with the hand lever J³, the arrangement being such that when the upper magazine is in 95 operative position, the locking device engages the grip portion of the hand lever and prevents its operation, whereas when the lower magazine is in such position, the locking device is disengaged from the hand lever and permits its operation. 100

The following improvement, although illustrated only in connection with the supplemental magazines, is equally applicable to the main magazines. As shown in Fig. 1, the magazine entrances D¹ are pivoted, as at D², to the respective magazine base-frames B¹, the upper entrance being held in place by the customary spring D³, and the lower entrance by the improved spring arrangement set forth in my prior patent No. 1,386,786. As more fully disclosed in said 110 patent, this arrangement comprises the torsion springs D⁴ connected at their inner ends to the enclosed rock shaft D⁵ and engaged at their outer ends with the ribbed members 115 of the entrance frame. The rock shaft D⁵ is journaled in suitable bearings in the entrance frame and is provided at opposite ends with the arms D⁶ which carry rollers D⁷ arranged in engagement with the underside of the base frame. These arms D⁶, by 120 reacting against the base-frame, maintain the torsion springs D⁴ under sufficient tension to hold the entrance up in its operative position and at the same time permit it to be turned downwardly about its pivot D² to 125 130

give access to the interior parts. In said Patent No. 1,386,786, the rollers D⁷ are allowed to run along the plain underface of the magazine base-frame in the opening and closing movements of the magazine entrance, but in the present instance, according to my invention, the base frame is provided with raised portions or abutments D⁸ arranged in the path of movement of the rollers. The location of the abutments is such that they will engage the rollers D⁷ at opposite sides in their two terminal positions and thus offer sufficient resistance to their movement in either direction to hold the magazine entrance in its opened or closed condition.

As previously stated, I have shown my improvements only in preferred form and by way of example, and obviously many modifications and alterations therein and in their mode of application will suggest themselves to those skilled in the art without departure from the scope of the invention.

Having thus described my invention, its construction and mode of operation, what I claim is as follows:

1. In a typographical machine, the combination of two series of matrix magazines arranged side by side or in tandem, distributing mechanism cooperating continuously with all the magazines of both series, assembling mechanism common to the two series, and supporting and shifting means whereby any selected magazine of either series may be moved into operative relation to the assembling mechanism without disturbing the cooperative relation existing between the magazines and the distributing mechanism.

2. In a typographical machine, the combination of two series of matrix magazines arranged side by side or in tandem, and each magazine provided with escapements, distributing mechanism cooperating continuously with all the magazines of both series, a set of key controlled escapement actuating reeds for each series, and supporting and shifting means whereby any selected magazine of either series may be moved into operative relation to its corresponding set of escapement actuating reeds without disturbing the cooperative relation existing between the magazines and the distributing mechanism.

3. In a typographical machine, the combination of two series of matrix magazines arranged side by side or in tandem, and each magazine provided with escapements, distributing mechanism cooperating continuously with all the magazines of both series, an assembler entrance common to the two series, a set of key controlled escapement actuating reeds for each series of magazines, and supporting and shifting means whereby any selected magazine of either series may be brought into operative relation to the as-

sembler entrance and its corresponding set of escapement actuating reeds without disturbing the cooperative relation existing between the magazines and the distributing mechanism.

4. In a typographical machine, the combination of two series of matrix magazines arranged side by side or in tandem, a plurality of distributors, each cooperating continuously with the opposite magazines of the two series, an assembler entrance common to the two series, means for mounting the magazines of each series so as to permit them to turn about separate and independent pivotal axes located adjacent the corresponding distributors, the axes of one series being coincident with the axes of the other series, and means for shifting the magazines of either series about their pivotal axes to bring any selected one into operative relation to the assembler entrance.

5. In a typographical machine, the combination of a main matrix magazine, a plurality of supplemental matrix magazines arranged at the side thereof, assembling mechanism common to the several magazines, distributing mechanism cooperating continuously with all said magazines, and supporting and shifting means whereby one or another of the supplemental magazines may be moved into operative relation to the assembling mechanism without disturbing their cooperative relation with the distributing mechanism.

6. In a typographical machine, the combination of two series of shiftable matrix magazines, and means for shifting both series of magazines simultaneously in the same direction to bring two different magazines into operative position at one operation.

7. In a typographical machine, the combination of two series of suitable matrix magazines, and means for shifting the two series, either independently or simultaneously, to bring different selected magazines into operative position.

8. In a typographical machine, the combination of two series of shiftable matrix magazines, shifting means for each series, and a coupling device for connecting the two shifting means together, when desired, so that both may be operated as one.

9. In a typographical machine, the combination of two series of shiftable matrix magazines, two shifting hand levers, one for each series, arranged in close proximity to each other, and a coupling device carried by one lever and adapted to engage the other to lock the two together for simultaneous operation when desired.

10. In a typographical machine, the combination of a plurality of distributors, a corresponding plurality of matrix magazines mounted to turn about separate and inde-

pendent pivotal axes located adjacent the respective distributors, and means for shifting the magazines about their pivotal axes to bring one or another into operative position, the said magazines being arranged in planes converging toward their upper ends, for the purpose described.

11. In a typographical machine, the combination of a plurality of magazines, a shift frame movable to bring one or another of the magazines into operative position and comprising separable base frames whereon the magazines are removably mounted, means for effecting the separation of the base frames to permit the removal of the magazines, and means for preventing the separation of the base frames when the shift frame occupies a given position.

12. In a typographical machine, the combination of a plurality of magazines, a shift frame movable to bring one or another of the magazines into operative position, means for effecting such movement of the shift frame, additional means for moving the shift frame to an extent beyond that controlled by the first mentioned means, and locking means to prevent the operation of said additional means when the shift frame occupies a given position.

13. In a typographical machine, the combination of a fixed assembler entrance, a plurality of magazines, a shift frame movable to bring one or another of the magazines into operative relation to the assembler entrance and comprising separable base frames whereon the magazines are removably mounted, means for effecting such movement of the shift frame, additional means for moving the shift frame to locate the lowermost magazine beyond the assembler entrance and for separating the base frames from each other to permit the removal of the magazines, and locking means to prevent the operation of said additional means except when the lowermost magazine is in operative relation to the assembler entrance.

14. In a typographical machine, the combination of a fixed assembler entrance, a plurality of magazines, means for shifting the magazine to bring one or another into operative relation to the assembler entrance, additional means for raising the magazines above the assembler entrance, and locking means for preventing the operation of said raising means, except when the lowermost magazine is in operative relation to the assembler entrance.

15. In a typographical machine, the combination of a fixed assembler entrance, a plurality of distributors, a corresponding plurality of magazines operatively connected with the distributors, separate base frames whereon the magazines are removably mounted and each pivotally mounted at its upper end immediately adjacent the cor-

responding distributor, means for shifting the base frames about their respective pivots to bring one or another of the magazines into operative relation to the assembler entrance without affecting the connection of the magazines with the distributors, additional means for rocking the base frames to an extent beyond that controlled by the shifting means so as to locate the lowermost magazine beyond the assembler entrance, and locking means to prevent the operation of said additional means except when the lowermost magazine is in operative relation to the assembler entrance.

16. In a typographical machine, the combination of a fixed assembler entrance, a plurality of distributors, a corresponding plurality of magazines operatively connected with the distributors, separate base frames whereon the magazines are removably mounted and each pivotally mounted at its upper end immediately adjacent the corresponding distributor, means for shifting the base frames about their respective pivots to bring one or another of the magazines into operative relation to the assembler entrance without affecting the connection of the magazines with the distributors, additional means operable to separate the base frames from each other and to locate the lowermost magazine beyond the assembler entrance, and locking means for preventing the operation of said additional means except when the lowermost magazine is in operative relation to the assembler entrance.

17. In a typographical machine, the combination of a fixed assembler entrance, a plurality of distributors, a corresponding plurality of magazines operatively connected with the distributors, separate base frames whereupon the magazines are removably mounted and each pivotally mounted at its upper end immediately adjacent the corresponding distributor, means for shifting the base frames about their respective pivots to bring one or another of the magazines into operative relation to the assembler entrance without affecting the connection of the magazines with the distributors, a pair of cams for swinging the lower base frame relatively to the shifting means to locate the magazine thereon beyond the assembler entrance, a hand lever for operating said cams, and a locking device mounted on the machine frame in position to engage and hold the hand lever against operation except when the lowermost magazine is in operative relation to the assembler.

18. In a typographical machine, the combination of a magazine, a distributor, an intermediate pivoted magazine entrance, a torsion spring carried bodily by the entrance, a movable device connected to said spring and arranged to react against a relatively fixed part of the machine, and an

abutment arranged in the path of movement of said device and acting to resist its movement in either direction.

19. In a typographical machine, the combination of a magazine, a distributor, an intermediate pivoted magazine entrance, a rock shaft carried by the entrance, a torsion spring surrounding the shaft and connected thereto at one end and at its opposite end to

the entrance, an arm fixed to the shaft and arranged in running engagement with a relatively fixed part of the machine, and an abutment arranged in the path of movement of said arm and acting to resist its movement in either direction. 15

In testimony whereof, I have affixed my signature hereto.

DAVID S. KENNEDY.
